UNITED STATES PATENT OFFICE

PHILIP D. DOHERTY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

RESETTING MECHANISM FOR WEFT-REPLENISHING LOOMS

Application filed March 14, 1929. Serial No. 347,094.

This invention relates to improvements in resetting mechanism for weft replenishing looms more particularly of the multicolor type and it is an important object of the invention to provide means for moving the shuttle feeler so that it may be relieved from objectionable contact with the lay.

In the usual multicolor weft replenishing mechanism there are provided two separate devices which act to reset the magazine on the transferring beat of the loom. One of these is the so-called shuttle feeler which is pivoted above the lay to be engaged and raised by the lay as it nears its extreme forward movement on a transferring pick of the loom. The other device includes a cam formed on the bottom of the transferrer latch which engages the bunter on the lay, the cam cooperating with the rod which extends upwardly and is operatively connected to the top rock shaft and shelf of the usual multicolor weft replenishing mechanism.

When the shuttle feeler performs no other function than to detect for the shuttle it is permissible that said feeler engage the lay in order to rock the top shaft, but when a thread cutter is mounted on the shuttle feeler it may be desirable to keep the shuttle feeler out of contact with the lay at all times in order to prevent injury to the cutting mechanism. This result may be accomplished by depending solely upon the cam of the latch to reset the magazine, but under certain conditions it is desirable to relieve the latch of the necessity for resetting the magazine due to the fact that an adjustment of said latch may be rendered necessary by a changed condition in the replenishing mechanism.

The latch is ordinarily adjustably mounted on a holder pivoted to the depending legs of the transferrer and during transfer energy derived from the bunter of the lay is transmitted through the latch and the holder to the transferrer, the latter extending backwardly toward the lay and engaging the bobbin to move it downwardly to the proper vertical position with respect to the shuttle. With a change in the throw of the crank shaft which operates the lay, or with a lowering of the lay due to wearing of the rocker

pins about which the lay oscillates, it may be desirable to change the position of the latch with respect to its holder so that when the lay is in its extreme forward position the transferrer will be effective to place the incoming bobbin correctly with respect to the shuttle. From this it will be seen that the transferrer latch is likely to be changed from time to time and for this reason it is desirable to reset the magazine through some mechanism other than the latch.

The interval during which resetting of the magazine may take place is that lapsing between engagement of the lay bunter with the latch, and arrival of the lay at its extreme forward position. In some looms this interval covers about an inch and a quarter of travel on the part of the lay, but the resetting is not accomplished until the very end of this interval. It is an important object of my present invention to effect resetting at an earlier point in this interval so that the shuttle feeler and its thread cutter may be moved in advance of the lay to prevent the latter from injuring the cutter.

The previously mentioned latch-lifting rod which is a customary part of the ordinary weft replenishing mechanism lies adjacent the transferrer arm and is operatively connected to the top rock shaft. It is a further object of my present invention to establish connections between the transferrer arm and said rod so that the rock shaft may be restored to normal position by a force derived from the transferrer arm during an early part of the previously mentioned interval of time. If desired a yielding connection may be established between the transferrer arm and said rock shaft so that the transferrer mechanism may continue to move after the magazine is reset without injuring any parts of the magazine.

With these and other objects in view which will appear as the description proceeds, my invention resides in the combination and arrangement of parts hereinafter described and set forth in the claims.

In the accompanying drawings, wherein I have shown a particular form of shuttle feeler and thread cutter,

Fig. 1 is an end elevation of a weft replenishing mechanism provided with my invention as viewed from the center of a loom, and

Fig. 2 is a front elevation taken in the direction of arrow 2, Fig. 1.

Referring to the drawings, I have shown a loom frame designated generally at 10 on which is mounted the inside plate 11 of a weft replenishing magazine M. The plate has mounted therein a stud 12 held in adjusted longitudinal and angular position with respect to the plate by set screw 13. Mounted on said stud is a transerrer arm 14 having depending legs 15 to which is pivoted as at 16 a latch holder 17. The latter supports the latch 18 which is held in adjusted horizontal position with respect to the holder by means of screw 19. The latch is adapted for engagement with the bunter 20 on the lay L so that as the lay moves forwardly with the latch raised said bunter will engage the latch to cause counter-clockwise movement of the transerrer arm around stud 12 as viewed in Fig. 1. The downward movement of the left hand end of the transerrer arm effects transfer of the bobbin not shown.

The latch is normally down or below the position shown in Fig. 1, and is raised by means of a lifting rod 21 which extends around the bottom of the latch to support the latter. The upper end of the rod may be provided with a rod head 22 pivoted as at 23 to an arm 24 of a rock lever 25 pivoted to the frame of the magazine as at 26. The opposite arm 27 of the lever 25 is slotted to receive a sliding block 28 pivoted to a stud 29 carried by arm 30. The latter is secured by set screw 31 to a rock shaft 32 located at the top of the magazine. A compression spring 33 located between the block 28 and the arm 27 yielding resists relative movement of the lever 25 and the arm 30, the block sliding in the slot of the arm 27.

The top rock shaft oscillates in bearings 34 formed as fixed parts of the magazine frame and has secured thereto a shelf member 35 formed with hubs 36 at the ends thereof which are held to said shaft by set screws 37. The rear end of the shaft 32 projects beyond the rear bearing 34 and has secured thereto an arm 38 having pivotally connected thereto the upper end of a shuttle feeler controlling rod 39.

Upright slides 40, one for each cell of the magazine and shuttle of the loom, cooperate with the shelf 35 and are controlled by a so-called color slide 41 which has both longitudinal and rocking movements, the longitudinal movements being under control of the shuttle boxes and the rocking movements being due to a cam.

The lower end of rod 39 is connected as at 42 to a shuttle feeler holder 43 pivoted as at 44 to a fixed stud. The shuttle feeler 45 is secured for adjustable longitudinal motion

with respect to the holder 43 by means of screw 46. The shuttle feeler ordinarily has a downwardly and forwardly curved surface 47 adapted for engagement with a portion of the lay to effect upward movement of the shuttle feeler and therefore rocking movement of the top shaft 32, the result of which is to cause such a movement of the arm 30 and lever 25 as will depress the latch 18.

The shuttle feeler has pivotally mounted thereon as at 48 a movable cutter blade 49 which is attached by means of a rod 50 to a fixed stud 51. The rising and falling movements of the shuttle feeler will cause relative movement of the cutter 49 with respect to the shuttle feeler because of the fact that the studs 44 and 51 are eccentric with respect to each other.

It is believed that the descriptive matter thus far given will provide an understanding of the operation of the magazine. Further reference may be had to prior patent to Ryon No. 1,030,748 which shows the magazine parts and to patent to Chevrette No. 1,662,235 which shows the particular form of combined shuttle feeler and thread cutter which is supported on stud 44.

As previously stated my present invention relates to means for moving the shuttle feeler without engagement with the lay so that the latter will not engage the cutter to damage the same, and in carrying my invention into effect I mount a collar 60 on the rod 21 so that the same may be adjusted as to vertical position by means of a set screw 61. A clip 62 is held to the transerrer arm by means of a screw 63, said clip extending as shown in Fig. 2 and being perforated as at 64 to receive the rod 21. A compression spring 65 is interposed between the bottom of the clip and the top of the collar, said spring 65 being sufficiently strong to overcome the spring 33.

Under normal conditions the transerrer arm will be in the raised position indicated in Fig. 1, being held in this position yielding by a spring S the form and function of which is well understood. At the time of transfer the arm 14 will descend to the dotted line position shown in Fig. 1 and during the first part of this descent the clip 62 will exert a compressing force on the spring 65, and the latter in turn will tend to depress the rod 21. At some time prior to the arrival of the transerrer arm at its lowest position and before the lay has opportunity to engage the shuttle feeler, the spring 65 will be effective to move the collar 60 and therefore the rod 21 down to its normal position, thereby rocking the lever 25 and arm 30 from the full line to the dotted line position shown in Fig. 2. This movement of arm 30 causes a rocking of shaft 32 so that the arm 38 rocks in a counter-clockwise direction with reference to Fig. 2 to lift the rod 39 and therefore the shuttle feeler. It will be noted that this operation

is independent of any cam on the latch 18 and does not depend upon engagement of the lay with the shuttle feeler.

From the foregoing it will be seen that I have provided a very simple means adaptable to multicolor weft replenishing mechanism at present in use and effective to reset the magazine without engagement between the lay and the shuttle feeler and without engagement between the lower end of the rod 21 and any cam formed on the bottom of the latch 18, the resetting being effected through a connection between the transerrer arm and a part of the mechanism which moves with the shuttle feeler. It will further be noted that I employ the same rod to effect the early resetting of the magazine which is used to set the latch 18 for engagement with the bunter 20 of the lay and that the latch will be held raised in proper position to engage the bunter until after the latter engages the latch, this relation existing because of the fact that the rod 21 cannot move downwardly until a force derived from the descending transerrer arm is transmitted through the spring 65 to said rod. The transerrer arm may continue to move downwardly after the top shaft 32 is reset but this will not strain or break any part of the magazine, the only effect being to cause a further compression of the spring 65.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a lay, a combined shuttle feeler and thread cutter, a transerrer arm, a latch operatively connected to the arm and capable of engagement with the lay, operating connections between the shuttle feeler and the latch to act on transferring beats of the loom to move the latter into operative relation with respect to the lay and also to move the shuttle feeler into shuttle detecting position in the path of the lay, and means movable with the transerrer arm independent of the latch to engage said connections and move the latter to move the combined shuttle feeler and cutter out of the path of the lay during the forward movement of the lay to prevent engagement of the lay and combined feeler and cutter.

2. In a weft replenishing loom having a lay, a combined shuttle feeler and thread cutter, a transerrer arm, operative connections for the shuttle feeler to move the latter into shuttle detecting position in the path of the lay on a transferring beat of the loom, an element operatively connected to the transerrer and movable on a transferring beat of the loom into operative relation with respect to the lay, and a member independent of the

element mounted on the transerrer arm and movable therewith to be operatively related to the connections during the forward stroke of the lay on a transferring beat of the loom to move said connections to cause the combined shuttle feeler and thread cutter to move out of lay engaging position before the lay completes its forward movement.

3. In a weft replenishing loom having a lay, a rocking member, a combined shuttle feeler and thread cutter operatively connected to the member, a transerrer arm, a latch for the arm operatively connected to the rocking member, said member on a transferring beat of the loom effective to move the shuttle feeler and cutter into shuttle detecting position in the path of the lay and also effective to move the latch into operative relation with respect to the lay, and means independent of the latch and mounted on the transerrer arm and movable with the latter on a transferring beat of the loom to actuate the member to cause the latter to move the combined shuttle feeler and thread cutter out of the path of the lay on a transferring beat of the loom before the lay arrives at a point in its forward movement where it would otherwise engage the shuttle feeler and cutter.

4. In a weft replenishing loom having a lay, a rocking member, a combined shuttle feeler and thread cutter operatively connected to the member, a transerrer arm, a latch for the arm operatively connected to the rocking member, said member on a transferring beat of the loom effective to move the shuttle feeler and cutter into shuttle detecting position in the path of the lay and also effective to move the latch into operative relation with respect to the lay, and a yielding connection between the transerrer arm and the member effective during the forward movement of the lay on a transferring beat of the loom to move said member to cause the shuttle feeler to move out of the path of the lay during the forward movement of the lay to prevent engagement of the lay and combined feeler and cutter.

5. In a weft replenishing loom having a lay, a combined shuttle feeler and thread cutter, a transfer mechanism to be operatively related to the lay on a transferring beat of the loom during the forward movement of the lay, devices effective on a transferring beat of the loom to move the shuttle feeler and cutter into shuttle detecting position in the path of the lay, and means to move the combined shuttle feeler and thread cutter out of the path of the lay during the forward movement of the lay to prevent engagement of the lay and combined feeler and cutter.

6. In a weft replenishing loom having a lay, a combined shuttle feeler and thread cutter, a transerrer arm, a latch operatively connected to the transerrer arm and capable of engagement with the lay to cause actuation

of the arm, a control member operatively connected to the shuttle feeler and cutter, an element operatively interposed between the latch and the control member, said control member effective to move the combined shuttle feeler and thread cutter into the path of the lay to detect for shuttle presence and effective to move the latch by means of said element into operative relation with respect to the lay, and connections between the transerrer arm and said element independent of the latch and effective during the transferring stroke of the arm to cause movement of the control member, thereby causing the latter to move the combined shuttle feeler and thread cutter out of the path of the lay.

7. In a weft replenishing loom having a lay, a combined shuttle feeler and thread cutter, a transerrer arm, a latch operatively connected to the transerrer arm and capable of engagement with the lay to cause actuation of the arm, a control member operatively connected to the shuttle feeler and cutter, an element operatively interposed between the latch and the control member, said control member effective to move the combined shuttle feeler and thread cutter into the path of the lay to detect for shuttle presence and effective to move the latch by means of said element into operative relation with respect to the lay, a yielding connection interposed between the transerrer arm and the element and effective during the first part of the transferring stroke of the transerrer arm to cause movement of the element by a force derived from the transerrer arm to move the control member, thereby causing the latter to move the combined shuttle feeler and thread cutter out of the path of the lay during the forward movement of the lay to prevent engagement of the lay and combined feeler and cutter.

8. In a weft replenishing loom having a lay, a combined shuttle feeler and thread cutter, a transerrer arm, a latch operatively connected to the transerrer arm and capable of engagement with the lay to cause actuation of the arm, a control member operatively connected to the shuttle feeler and cutter, an element operatively interposed between the latch and the control member, said control member effective to move the combined shuttle feeler and thread cutter into the path of the lay to detect for shuttle presence and effective to move the latch by means of said element into operative relation with respect to the lay, a clip carried by the transerrer arm, a spring associated with the element to be engaged by the clip during downward movement of the transerrer arm to cause movement of the element by a force derived from the transerrer arm, said control member when the element moves under influence of the transerrer arm effective to move the

combined shuttle feeler and thread cutter out of the path of the lay.

9. In a weft replenishing mechanism having a lay, a combined shuttle feeler and thread cutter, a rocking member connected to the shuttle feeler and cutter and effective when rocked in one direction to move the feeler and cutter into the path of the lay and when moved in another direction to move the feeler and cutter out of the path of the lay, an element connected to and moving with the rocking member, a transerrer arm controlled by the element, and means actuated by the transerrer arm during the forward movement of the lay to move the shuttle feeler and cutter out of the path during the forward movement of the lay to prevent engagement of the lay and combined feeler and cutter.

10. In a weft replenishing loom having a lay, a combined shuttle feeler and thread cutter, a transerrer arm, operating connections effective on a transferring beat of the loom to move the combined feeler and cutter into the path of the advancing lay to detect for a misplaced shuttle and also to render the transerrer arm operative by the advancing lay to have a transferring movement, and means actuated by the transerrer arm during the forward movement of the lay to move the operating connections to move the combined feeler and cutter out of the path of the lay during the forward movement of the lay to prevent engagement of the lay and combined feeler and cutter.

In testimony whereof I have hereunto affixed my signature.

PHILIP D. DOHERTY.
